by Walter G. Lombard,
Atty.

UNITED STATES PATENT OFFICE.

FRANK L. GORMLEY, OF BROOKLINE, MASSACHUSETTS.

STOP MECHANISM FOR LIFTING-JACKS.

1,380,375.

Specification of Letters Patent. Patented June 7, 1921.

Application filed January 20, 1921. Serial No. 438,540.

To all whom it may concern:

Be it known that I, FRANK L. GORMLEY, a citizen of the United States of America, and a resident of Brookline, in the county 5 of Norfolk and State of Massachusetts, have invented certain new and useful Improvements in Stop Mechanism for Lifting-Jacks, of which the following is a specification.

This invention relates to stop mechanisms 10 for lifting jacks and particularly that class of lifting jacks known as screw jacks.

The object of the invention is the production of a device of this character which will operate automatically to prevent the movable member of the jack from passing beyond the point of safety.

The invention consists of certain novel features of construction and arrangement of parts which will be understood readily by 20 reference to the description of the drawings and to the claims to be hereinafter given.

For the purpose of illustrating the invention, one preferred form thereof is illustrated in the drawings, this form having 25 been found to give satisfactory and reliable results although it is to be understood that the various instrumentalities of which the invention consists can be variously arranged and organized and the invention is not limited to the precise arrangement and organization 30 of these instrumentalities as herein shown and described except as required by the scope of the appended claims.

Of the drawings—

35 Figure 1 represents a horizontal section of a portion of a screw jack showing in plan a stop mechanism embodying the principles of the present invention.

40 Fig. 2 represents a vertical section of the same on line 2, 2, on Fig. 1.

Fig. 3 represents a horizontal section, similar to Fig. 1, with the upper toothed plate removed.

45 Fig. 4 represents an inverted plan of the upper toothed plate.

Fig. 5 represents an elevation of the upper end of the standard and showing in elevation the toothed upper plate removed from coaction with the teeth formed upon 50 or secured to the upper end of said standard, and

Fig. 6 represents a vertical section of a lifting jack with the improved stop mechanism applied thereto.

55 Similar characters indicate like parts

throughout the several figures of the drawings.

In the drawings, 10 represents a suitable base supporting a stationary standard 11 over the outer periphery of which is fitted 60 a movable sleeve 12, to the upper end of which is threaded a cap 13.

In the upper end of the standard 11 is mounted a nut 14 to which is threaded a lifting screw 15 having splined to its upper 65 reduced end a bevel gear 16 with which meshes a bevel gear 17 formed upon or secured to a revoluble shaft or spindle 18, the outer end of which is provided with a suitable operating mechanism 19 of any well 70 known construction.

Between the upper face of the bevel gear 16 and the inner face of the cap 13 are two annular plates 20, 21, between which are interposed a plurality of anti-friction 75 members 22.

The movable member 12 is provided on one side with a flanged projection 24 having a removable plate 25 secured thereto by bolts 25.

The plate 25 is provided with a bearing 26 for the spindle or shaft 18 and secured to the hub of the gear 17 is a ratchet wheel 27.

The bearing 26 extends through a cylindrical boss 28 on the inner face of the plate 25 and on this boss 28 is loosely mounted the gear wheel 29 having secured to one face thereof a plurality of pawls 30 coacting with said ratchet wheel 27.

Beneath the gear wheel 29 is a revoluble shaft 35 having secured thereto a pinion 36 meshing with said gear 29 and driven thereby when the movable member 12 of the jack is being lowered.

The shaft 35 has also secured thereto a worm wheel 37 which meshes with a worm 38 revoluble in bearings in the bracket 39 secured to the inner face of the removable plate 25.

As thus far described, the lifting jack is the same as that shown in Patent No. 1,324,345 issued to me Dec. 9, 1919. The worm 38 may have secured thereto any suitable brake mechanism such as that shown in 105 the aforementioned patent.

As the operating mechanism of the jack forms no part of the present invention, it is believed that it is unnecessary to show the same in detail as reference may be made 110

to the patent above referred to for a more complete description of the means of operating the jack.

It is obvious that some other form of actuating mechanism may be used equally as well as that shown in my earlier patent, the invention being adapted to be used on any form of screw jack in which a sleeve moves endwise on a supporting standard.

10 The standard 11 is provided in its upper end with two cylindrical chambers 40 in which is positioned the cylindrical extensions 41 of a plate 42 disposed upon the standard 11 and having an opening therein 15 through which the lifting screw 15 extends.

Each cylindrical extension 41 has a cylindrical depression 43 therein in which is mounted a helical spring 44.

Each helical spring surrounds a bolt 45 threaded to the standard 11 and having a head 46 in a recess 47 in the upper face of the plate 42.

25 The head 46 forms a shoulder for the upper end of the spring 44 which spring tends to move the plate 42 downwardly and retain it under normal conditions in its lowermost position.

20 The plate 42 is provided with a plurality of ratchet teeth 48 engaging with a plurality of teeth 49 formed upon an annular plate 50 secured to the upper end of the revolute nut 14.

35 The nut 14 under abnormal conditions is freely revolute about the axis of the standard 11 and in order to reduce the friction when the nut 14 is revolved, said nut is mounted upon an anti-friction support consisting of two annular plates 51 and 52 with a plurality of balls or similar rolling members 53 interposed between said plates.

40 The ratchet teeth 48 and 49 are so constructed that during the lifting movement of the screw 15 the vertical edges of said teeth are in engagement and as a consequence the nut 14 is locked from rotation.

45 It is self-evident therefore, that when the actuating mechanism 19 is operated to lift a load the nut 14 will be held from rotating and the rotation of the screw 15 therein will cause the screw 15 to be moved upwardly carrying therewith the sleeve 12.

50 This sleeve 12 is provided with a shoulder 54 which is formed in said sleeve at a predetermined point so that when the sleeve in its upward movement reaches the limit of safety the said shoulder will come into contact with the ends of the plate 42 and lift said plate against the tension of the springs 44 until the teeth 48 and 49 are disengaged.

55 60 After these teeth 48 and 49 have been disengaged, the nut is freely revolute and will rotate with the screw without imparting any upward movement to said screw.

65 As soon as the teeth 48 and 49 have been disengaged, the bottom wall of the de-

pressions 47 will come into contact with the under faces of the heads 46 of the screws 45 and limit further upward movement of said plate 42.

As soon as the sleeve is permitted to lower 70 under its load the springs 44 will operate and return the plate 42 to its normal position with the teeth 48 thereon in engagement with the teeth 49.

This makes a very effective stop mechanism for lifting jacks which is simple in construction.

It has a particular advantage in being located within the sleeve 12 where it cannot be tampered with.

80 It is believed that the operation and many advantages of the invention will be understood without further description.

Having thus described my invention, I claim—

85 1. In a lifting jack, a standard; a nut therein normally locked from rotation; a revolute screw therein; a sleeve surrounding the standard and movable endwise with said screw; and means actuated by the movement of said sleeve for unlocking said nut and permitting its free rotation with said screw.

90 2. In a lifting jack, a standard; a nut therein normally locked from rotation; anti-friction members supporting said nut; a revolute screw in said nut; a sleeve surrounding the standard and movable endwise with said screw; and means actuated by the movement of said sleeve for unlocking said nut and permitting its free rotation with said screw.

95 3. In a lifting jack, a standard; a nut therein normally locked from rotation; ratchet teeth on the upper end of said nut; a revolute screw in said nut; a sleeve surrounding the standard and movable endwise with said screw; a non-revolute plate provided with teeth adapted to coact with the teeth of said nut and provided with projections in the path of movement of shoulders on said sleeve; and means for normally retaining the two sets of teeth in engagement.

100 4. In a lifting jack, a standard; a nut therein normally locked from rotation; ratchet teeth on the upper end of said nut; a revolute screw in said nut; a sleeve surrounding the standard and movable endwise with said screw; a non-revolute plate provided with teeth adapted to coact with the teeth of said nut and provided with projections in the path of movement of shoulders on said sleeve; and resilient means for normally retaining the two sets of teeth in engagement.

105 5. In a lifting jack, a standard; a nut therein normally locked from rotation; ratchet teeth on the upper end of said nut; a revolute screw in said nut; a sleeve sur-

rounding the standard and movable endwise with said screw; a non-revoluble plate provided with teeth adapted to coact with the teeth of said nut and provided with 5 projections in the path of movement of shoulders on said sleeve, said plate having depressions therein; headed bolts extending through said depressions and secured to the standard; and springs surrounding said 10 bolts.

6. In a lifting jack, a standard having cylindrical chambers in the upper end thereof; a nut in said standard and revoluble therein; ratchet teeth on the upper end of 15 said nut; a plate having ratchet teeth adapted to coact with the teeth of said nut and prevent the rotation of said nut; recessed projections on said plate positioned in said chambers; headed bolts extending through 20 said projections and secured to said standard; springs surrounding said bolts; a revoluble screw in said nut; and a sleeve movable endwise with said screw and provided with a shoulder adapted to engage said 25 plate and move it against the tension of said springs until the two sets of teeth are disengaged.

7. In a lifting jack, a standard having cylindrical chambers in the upper end thereof; a nut in said standard and revoluble therein; ratchet teeth on the upper end of 30 said nut; a plate having ratchet teeth adapted to coact with the teeth of said nut and prevent the rotation of said nut; recessed 35 projections on said plate positioned in said chambers; headed bolts extending through said projections and secured to said standard; springs surrounding said bolts; a revoluble screw in said nut; a sleeve movable 40 endwise with said screw and provided with a shoulder adapted to engage said plate and

move it against the tension of said springs until the two sets of teeth are disengaged; and means for limiting the upward movement of said plate. 45

8. In a lifting jack, a standard; a nut therein and freely revoluble; a revoluble screw in said nut; and means mounted on the upper end of said standard for normally preventing rotation of said nut and adapted to be actuated in the lifting operation at a predetermined time to release said nut and permit its rotation. 50

9. In a lifting jack, a standard; a nut therein and freely revoluble; a revoluble 55 screw in said nut; a sleeve surrounding said standard and movable endwise with said screw; and means mounted on the upper end of said standard for normally preventing rotation of said nut and adapted to be 60 actuated in the upward movement of said sleeve to release said nut and permit its rotation.

10. In a lifting jack, a standard; a nut therein and freely revoluble; a revoluble 65 screw in said nut; a sleeve surrounding said standard and movable endwise with said screw; means mounted on the upper end of said standard for normally preventing rotation of said nut and adapted to be actuated in the upward movement of said sleeve to release said nut and permit its rotation; and means for preventing farther upward movement of said sleeve when the nut has 70 been released. 75

Signed by me at 294 Washington St., Boston, Mass., this 18th day of January, 1921.

FRANK L. GORMLEY.
